[57] CLAIM

The ornamental design for a removable storage container, as shown and described.

DESCRIPTION

FIG. 1 is a perspective view of a storage container in accordance with the present invention shown with the drawer closed in accordance with the present invention. FIG. 2 is a similar to FIG. 1 but with the drawer shown in an open position.

FIG. 3 is a front elevational view of the storage container illustrated in FIG. 1.

FIG. 4 is a rear elevational view of the storage container illustrated in FIG. 1.

FIG. 5 is side elevational view of the storage container illustrated in FIG. 1 illustrating the right side relative to FIG. 1.

FIG. 6 is similar to FIG. 5 but illustrating the left side.

FIG. 7 is a top plan view of the storage container illustrated in FIG. 1.

FIG. 8 is bottom plan view of the storage container illustrated in FIG. 1; and,

FIG. 9 is a rear elevational view of the storage container illustrated in FIG. 1.

The broken line showing of slots in FIG. 2 is for illustrative purpose only and forms no part of the claimed design.
